(57) **CLAIM**

The ornamental design for a paper towel holder, as shown and described.

DESCRIPTION

FIG. 1 is a perspective view showing the new design for a paper towel holder;

FIG. 2 is a front view thereof, a rear view being a mirror image thereof;

FIG. 3 is a top view thereof;

FIG. 4 is a bottom view thereof;

FIG. 5 is a left side view thereof, a right side view being a mirror image thereof;

FIG. 6 is a perspective view illustrating an alternative embodiment;

FIG. 7 is a perspective view illustrating an alternative embodiment; and,

FIG. 8 is a perspective view thereof showing the paper towel holder with a roll of paper towel.

The portions in Figures shown in broken lines form no part of the claimed design. Oblique line shading in FIGS. 6 and 7 is used to show transparent or translucent materials.
